UNIVERSAL PAINT STRIPER

Alf V. Eklov, Detroit, Mich., assignor to
Hilma C. Gettner, Detroit, Mich.

Application December 23, 1946, Serial No. 718,005

2 Claims. (Cl. 91—62.5)

1

My invention relates to a paint striping instrument especially adapted to automobile body and machinery striping, and like work.

The object of my invention is to produce a universal paint stiper that will operate automatically, and will seal the paint flow channel whenever the stiper is released.

Another object is to provide a universal stiper, equipped with interchangeable striping units, all connected with the paint supply channel, and operative by automatic means.

A further object is to provide a universal paint striping instrument that is simple in construction, easily and efficiently operated, and that can be manufactured at a very low cost.

These several objects are attained in the preferred form by the construction and arrangement of parts more fully hereinafter set forth.

Similar parts on all drawings are marked by similar numerals or letters.

Fig. 1 is a side elevation of my universal paint stiper, showing the general arrangement of the exterior operating units.

Fig. 2 is a top view of the assembled stiper unit, showing the relative position of the various operating lever and connected valves.

Fig. 3 is an end view of the stiper body taken on the line 3—3 of the Fig. 1, showing the body tubular design.

Fig. 4 is a longitudinal section taken on the line 4—4 of the Fig. 2, showing the relative position of the continuous paint passages leading through the paint stiper body and assembled operating units.

Fig. 5 is another longitudinal sectional view taken on the line 5—5 of the Fig. 1, showing the channel connection between the adjoining tubular frame sections, and the closing valve therebetween.

Fig. 6 is also a cross-sectional view taken on the line 6—6 of the Fig. 1, showing the clamp recesses for the respective stiper units.

Fig. 7 is a cross-sectional view of the universal stiper head disc taken on the line 7—7 of the Fig. 1, showing the radial paint passages leading therethrough to the respective striping units.

Fig. 8 is an enlarged cross-sectional view of one of the stiper units also taken on the same line 7—7 of the Fig. 1, showing the detailed construction of a stiper unit assembly.

In general, my universal paint stiper comprises a hollow tubular handle casing, provided with an angularly positioned stiper head frame threadably mounted on one end thereof, and which carries a multiple head disc rotatably

2

mounted on the outer end thereof, each bearing different types of striping units. The tubular casing and connected mechanism are provided with connected valve, and control means for automatically operating the stiper.

I will now describe more fully the detailed construction of my device, referring to the drawings and the marks thereon.

The paint chamber is made of a tubular casing 1, closed at one end, but having a paint passage channel *r* formed therethrough along the casing axis, and is provided with a closing cap 2 threadably mounted within the outer end thereof. The casing is preferably made of light metal, such as aluminum, or any other suitable metal. The closed casing end *a* is formed with a threaded end connecting nipple *b* projected therefrom, positioned concentric with the casing axis, and carries threadably mounted thereon a stiper head section 3, preferably designed and positioned at a predetermined angle with the attached casing 1. The head section 3 is cylindrical in form and made of the same material as the casing, and is designed with an end slot recess 4 of uniform width, positioned symmetrically with the section axis, cross-wise thereof, as indicated in the Fig. 1 of the drawings. A circular stiper head disc 5 is rotatably mounted within the recess 4 by means of the bearing pin 6 fixedly mounted cross-wise through the head section slot walls, and at right angles thereto. Suitable disc stiper units 7, each of a different width, are radially mounted on the stiper head disc 5, uniformly positioned thereon, and provided with radially positioned paint channels *c* leading to each of said units 7. Each channel *c* opens into the central disc head bearing *d*, as illustrated in the Fig. 7, showing three stiper units in combination, although more stiper units may be applied, if desired. Each stiper unit 7 is formed of a hollow casing section *e*, flattened and open at the outer end thereof, and carries a special striping disc *f* rotatably mounted therein, positioned with the disc edge projected slightly out from the casing end opening. The stiper discs *f* are thin flat circular discs formed with finely knurled edges, but each disc of a different width, and each completely filling their respective casing slot, yet rotatable therein. The disc casing sections *e* are formed with an inner pivot end mounting *g* for fixedly mounting same in the head disc 5, by pressed fit within the disc recess, or any other suitable means, and are provided with paint passage channels *h*, connecting the stiper head disc channels *c* with the respective

striper discs β . The bearing pin δ is provided with an off-set S-shaped paint passage k formed therein, designed with the inner passage end opening along the head section 3 centerline toward the outer end thereof, positioned to coincide with one of the head disc 5 paint passages c when the respective striper units 7 are rotated to their operative end position, and as indicated in the Figs. 1 and 4 of the drawings. The striper head disc 5 is held in operative position by the thumb screw 8 threadably mounted in the head section 3 slot wall, positioned therein to engage the corresponding lock recess m of the disc 5 opposite the chosen striper unit 7 , securely clamping said disc 5 in operative position. The outer end of the S-shaped paint passage k of the bearing pin δ , is extended to one side of the head section 3 , and opens into a side paint passage p extended along the outer section wall and into the threaded head mounting recess q coinciding with the tubular casing paint passage r , providing a complete and continuous paint passage from the paint chamber A to the selected operating striper unit 7 positioned at the outer head section end. A special plunger valve 9 is slidably mounted across the closed end of the tubular casing 4 through the cylindrical valve chamber s positioned to intersect the paint passage r at right angles thereto. The valve plunger 9 is provided with a valve port t positioned crosswise thereof to coincide with and intercept the paint passage r when said valve 9 is fully depressed within the valve chamber, thus automatically opening the paint passage for striper operations, or closing said paint passage when said valve 9 is displaced by reaction of the attached coil spring 10 , as shown in the Fig. 5. Along one side of the tubular casing 4 , near the central section thereof, is fixedly mounted a slotted bearing pin 11 , and carries pivotally attached thereto, an operating lever 12 extended nearly the full casing length and is provided with a thumb plate V at the inner end thereof. Near the inner end of the lever 12 is pivotally attached the projected end of the valve plug 9 , outside of the attached coil spring 10 , and provides convenient means for opening the paint passage valve whenever the paint striper is to be used. The opposite end of the lever 12 is pivotally attached to a special tapered air valve plug 13 mounted through a conical wall port w positioned near the capped end of the casing, allowing air to be admitted within the paint chamber A during painting operations, for relieving any vacuum as may be caused by the paint flow therefrom. Both of the valves 13 and 9 are automatically closed by release of pressure on the thumb plate V . When the proper striper unit 7 has been selected and positioned, and the head disc 5 locked in place, the striper is then ready for operation, and will function automatically as the thumb plate V is depressed by the operator.

Having fully described my universal paint striper, what I claim as my invention and desire to secure by Letters Patent is:

1. A universal paint striper, comprising a tubular body formed with a closable paint cham-

ber therein, a body head section mounted on one end thereof angularly positioned thereon, a circular head disc having a central bearing recess rotatably mounted within the outer end of the head section on a fixed cylindrical bearing pin formed with an S-shaped paint passage therethrough having side inlet and outlet ports, a disc locking screw mounted in the head section, positioned therein to engage the head disc face, predetermined paint striper units fixedly mounted around the outer head disc circumference, positioned radially thereon, radially positioned paint passages formed through the head disc leading from the central bearing recess to the respective disc striper units, each engageable with the bearing pin S-shaped paint passage outlet port positioned along the head disc centerline when disc is rotated to the forward outer position thereon, an inlet paint passage formed lengthwise through the head section connecting the paint chamber with the bearing pin S-shaped paint passage inlet port, and means for controlling the paint flow through the paint passage.

2. A universal paint striper adapted for making different types of paint stripe lines, comprising a tubular body formed with a closable paint chamber therein, a cylindrical head section having a central bearing mounted on one end of the tubular body, positioned at an angle thereto, a circular head disc rotatably mounted within the outer end of said head section on a fixed cylindrical bearing pin having an S-shaped paint passage formed therethrough having side inlet and outlet ports, means for locking the head disc in various rotated positions, predetermined disc paint striper units radially mounted around the head disc circumference, radially positioned paint passages formed through the head disc leading from the center bearing to the respective striper units, each engageable with the bearing pin S-shaped paint passage outlet port as the head disc is rotated thereover, an inlet paint passage formed lengthwise through the head section connecting the paint chamber with the bearing pin S-shaped paint passage side inlet port, a plug valve with cross-channel port, slidably mounted through the paint chamber body, intersecting the paint passage for opening and closing same, an air inlet valve mounted within the opposite paint chamber end, and spring operated lever means pivotally mounted on the paint chamber outer walls, connected to each of said valves, designed to automatically operate same, at will of the operator, when the striper is in use.
